UNITED STATES PATENT OFFICE.

ARTHUR S. S. FUSSELL, OF PHILADELPHIA, PENNSYLVANIA, ASSIGNOR TO JOHN F. SIMONS AND THOMAS MADDOCK, OF SAME PLACE, FREDERIC M. SIMONS, OF SWARTHMORE, PENNSYLVANIA, AND EDWARD S. SIMONS, OF ORANGE, NEW JERSEY.

DESIGN FOR A BUCKLE.

SPECIFICATION forming part of Design No. 27,205, dated June 15, 1897.

Application filed April 24, 1897. Serial No. 633,811. Term of patent 3½ years.

To all whom it may concern:

Be it known that I, ARTHUR S. S. FUSSELL, of the city and county of Philadelphia, State of Pennsylvania, have invented a new and original Design for Buckles, of which the following is a specification.

My invention is a new design for buckles such as are intended for personal wear and is illustrated in the accompanying drawings, 10 in which—

Figure 1 is a plan view of a buckle having my design, and Fig. 2 is a transverse sectional view of the same on the line $x-x$ of Fig. 1.

The design consists of the shape or form of 15 the buckle substantially as shown in the drawings. The body of the buckle is of U shape, with the two arms A A extending forward and

tapered and the edges rounded, as at a. The edges b of the end piece B are similarly rounded. A cross-bar C extends between the 20 tapered ends of the arms A A, and the tongue D is carried by the cross-bar.

Having now described my invention, what I claim as new, and desire to secure by Letters Patent, is as follows:

The design for a buckle substantially as herein shown and described.

In testimony of which invention I hereunto set my hand.

ARTHUR S. S. FUSSELL.
